TISSUE FEED-DOG DRIVING MECHANISM
OF SEWING MACHINES

Josef Keller, Jr., Rorschach, Switzerland

Application May 29, 1946, Serial No. 673,180
In Switzerland June 13, 1945

7 Claims. (Cl. 112—215)

1

The present invention relates to sewing machines and more particularly to the driving mechanism for the tissue feed-dog of such machines.

According to the invention the tissue feed-dog carrier is in operative connection with two rocking shafts by the intermediary of parallel guide lever means on the one hand and feed lever means acting transversally thereto on the other hand, respectively, which lever means are adapted to impart to said carrier a quadrangular motion.

The accompanying drawings illustrate, by way of example, one preferred embodiment of the invention.

Fig. 1 is a side elevation of the driving mechanism, partly in section.

Fig. 2 is a top plan view of the mechanism of Fig. 1, partly in section.

Fig. 3 is a front elevation as seen from the left hand side in Fig. 1.

Figs. 4 and 5 show two details, respectively to which reference is made in the ensuing specification, and

Fig. 6 is an exploded view, partly in perspective, of the mounting of the feed-lift rock levers made in accordance with the invention.

Referring now more particularly to the drawings, there is shown a machine frame 1 in which there is supported between two pivots 2 and 2', respectively, a feed advance rock shaft 3 which, in known manner, is operatively connected by the levers 4 and 5 with a stitch adjusting handle (not shown) and which shaft 3 is adapted to perform a rocking rotation through an angle which varies in accordance with the selectively adjusted stitch length. The rock shaft 3 has formed thereon two lever arms 6 which carry an axle 7. A broad link 8 rotatably connects the shaft 7 to a spindle 9 of the stirrup-shaped carrier 11 which carries the feed-dog 10 on a laterally projecting arm 11'. The carrier 11 is provided with two horizontal or rectilinear guideways 12 which extend in said carrier in opposite directions and which receive two roll pins 13 and 14 for reciprocal motion. The roll pin 13 is rotatably supported by the free end of a semi-circular downwardly curved lever 16 which is rigidly mounted on a feed-lift rock shaft 17 and which extends below and half way round the driving shaft 15 of the loop taker, which shaft is outlined in Fig. 3. The roll pin 14 is rotatably supported by one end of a lever 18 fixed on an axle 19 which, as seen in Fig. 6, for the purpose of an exact adjustment of the feed-dog carrier is eccentrically and rotatably mounted in a sleeve 21 having an eccentric bore 21'. Sleeve 21 is affixed by means of a set screw 23 to a frontal plate 1' of the machine frame 1. The curved lever 16 has formed therein a longitudinal slit 16', while the curved lever 18 is provided with a crank-like lateral pin or axle 18' which passes through this slit 16'. The shaft 17

receives its rocking rotation by the levers 20, 20' from a lifting eccentric (not shown) and this rocking rotation of the feed-lift rock shaft 17 causes the lever 16 to swing up and down. Upon oscillation of the lever 16, the same causes the lever 18 to swing up and down in an oscillation of equal size or angular extent as that of lever 16. The feed-lift rock levers 16 and 18 constitute together a parallel motion device which is adapted to impart to the feed-dog carrier 11, 11' and therewith to the tissue feed-dog 10 a vertical up and down motion. Besides this up and down motion the carrier 11, 11' together with the feed-dog 10 will be subjected to a horizontal motion, namely, a reciprocating movement transversally to the lever axes 17 and 19, by means of the feed advance rock levers 6 and the link 8. The combined driving action of the two lever means 6, 8 and 16, 18 the latter being of substantially equal length upon the feed-dog 10 causes the same to perform a complete horizontal and parallel quadrangular motion, the horizontal length of which corresponds to the adjusted stitch length and may be varied between zero and the predetermined limit by means of the stitch adjusting handle.

The feed-dog driving mechanism according to this invention is of simple and particularly strong construction which needs only little space and is, therefore, specially suitable for sewing machines having a free borne working support into which this mechanism may be readily built.

During the feeding motion of the tissue feed-dog the latter exerts upon the tissue to be fashioned a constant pressure so that the tissue will be steadily stressed on the whole feeding way.

Summarizing the aforesaid disclosure, it can thus be seen that the feed-dog 10 (Figs. 3, 4 and 5) is attached to a feed-bar or carrier 11 which is arched to provide two depending legs, the lower end portions of which are formed with horizontally disposed guideways 12. Projecting into one of the guideways 12 is the roll pin 13 carried on the rock-lever 16 and projecting into the other guideway is the roll pin 14 carried on the rock-lever 18. The rock-lever 16 is secured to one end of a feed-lift rock-shaft 17 for actuation thereby. The rock-lever 18 is pivoted at its rear end on an axle or pivot-stud 19 (Fig. 6) freely journaled in the bed of the machine, the rock-lever 18 being adapted to be oscillated or rocked about the pivot-stud 19 through its interconnection with the driven rock-lever 16.

Oscillation of the feed-lift rock-shaft 17 will impart rocking movements to the rock-lever 16 so as to cause the roll pin 13 to rise and fall in an arc about the axis of the rock-shaft 17. The rocking movements of the rock-lever 16 will effect a rocking of the rock-lever 18 about the axle 19, causing roller 14 to rise and fall simultaneously with roller 13. Since each of the rollers 13 and 14 enter the spaced guideways 12 provided

in the lower portions of the legs of the arched feed-dog carrier 11, the latter is caused to rise and fall vertically without any tipping of the feed-dog 10. Advance and return motions of the feed-dog 10 are derived from the feed-advance rock-shaft 3 through the rocker or link 6 and link 8.

Having thus described the invention, what is claimed as new and desired to be secured by Letters Patent, is:

1. A driving mechanism for the feed-dog of a sewing and like machine comprising a stirrup-shaped carrier connected to said feed-dog and having two downwardly depending legs, a transverse guideway provided in each leg, two levers pivotally connected to each other and shaped for attachment to said carrier, respective pivot means at one end of each lever and engaging said guideways, said levers being of substantially the same length from said pivot means to their location of pivotal connection, whereby said levers are adapted to impart reciprocal up and down motion to said feed-dog, means linked to said carrier for imparting to said feed-dog a reciprocal motion transversely to said first-named motion, and a rocking shaft journaled on said machine, the other end of one of said levers being under the influence of said rocking shaft, the other end of the other lever being pivoted on said machine.

2. A driving mechanism for the feed-dog of a sewing and like machine comprising a stirrup-shaped carrier connected to said feed-dog and having downwardly depending legs, a guideway in each leg and extending in lateral direction thereto, two levers pivotally connected to each other and shaped for attachment to said carrier, one end of each of said levers being pivoted in a respective guideway of said carrier, said levers being of substantially the same length from their location of pivotal connection to the pivoted ends, and respective driving means operatively connected to another end of one of said levers and to said carrier above said legs whereby reciprocal up and down motion, as well as a reciprocal motion in transverse direction to said first-named motion may be imparted to said feed-dog, the other end of the other lever being journaled on said machine.

3. A driving mechanism for the feed-dog of a sewing and like machine comprising a centrally located driving shaft, a stirrup-shaped carrier connected to said feed-dog and straddling above said driving shaft, substantially aligned lateral guideways extending in opposite directions and arranged in said carrier at either side of said driving shaft, two downwardly curved levers linked to each other at their median portions thereof and disposed below said shaft and said carrier, means slidably connecting said levers with said carrier in said guideways, and respective means operatively connected with one of said levers and with said carrier for imparting to said feed-dog reciprocal up and down motion as well as a reciprocal motion transversely to said first-named motion.

4. A driving mechanism for the feed-dog of a sewing machine comprising a carrier connected to said feed-dog, said carrier being provided with two laterally extending opposite guideways, two curved levers of substantially equal length linked to each other and extending substantially below said carrier, one end of each of said levers engaging a respective guideway for transmitting a reciprocal first movement to said feed-dog, a

rocking shaft, another end of one of said levers being operatively connected to said rocking shaft, whereby equal oscillatory movement of said shaft will be transmitted to said carrier by said one lever and said other lever linked to the former lever, and means linked to said carrier and imparting to the latter a second reciprocating movement transversely to said first movement.

5. A driving mechanism for transmitting to the feed-dog of a sewing and like machine a four-way motion comprising a parallel motion device including two levers linked at their median portions to each other, a carrier connected to said feed-dog and including rectilinear guideways,

15 one end of each of said levers pivotally engaging a respective guideway of said carrier and positioned on substantially equal level, whereby oscillatory movement imparted to one of said levers causes simultaneous motions of the same extent to both said levers and relatively to said carrier, and oscillatory means linked to said carrier and adapted to impart to the latter a reciprocal motion transversely to the motion caused by said levers.

25 6. A driving mechanism for transmitting to the feed-dog of a sewing and like machine a four-way motion comprising a parallel motion device including two levers linked at their median portions to each other and crossing thereat, a carrier connected to said feed-dog, one end of one

30 of said levers being arranged opposite and at substantially the same level as the one end of the other of said levers, the respective one ends of said levers pivotally engaging said carrier, 35 whereby oscillatory movement imparted to another end of one of said levers causes up and down motions to both said levers and relatively to said carrier, and oscillatory means linked to said carrier and adapted to impart to the latter a reciprocal motion transversely to the motion caused by said levers.

40 7. A work feeding mechanism for a sewing machine having a frame and a loop-taker drive shaft comprising a feed-dog, a carrier for said feed-dog arched to provide a pair of legs straddling said loop-taker drive shaft, feed-lift mechanism including a feed-lift rock shaft operatively connected to one of said feed-dog carrier legs adjacent the lower end of said one leg, feed ad-

45 vance mechanism including a feed advance rock shaft, feed advance rock lever means connected to said latter shaft, link means operatively connecting said feed advance rock lever means to said feed-dog carrier, and means supported by 50 the frame and connected to the other leg of the carrier for guiding said other leg during movements of the carrier and for maintaining the feed dog substantially level during operation of the machine.
